UNITED STATES PATENT OFFICE.

RALPH W. SOHL, OF AKRON, OHIO, ASSIGNOR TO THE GOODYEAR TIRE & RUBBER COMPANY, OF AKRON, OHIO, A CORPORATION OF OHIO.

VULCANIZING APPARATUS.

Application filed December 7, 1923. Serial No. 679,124.

To all whom it may concern:

Be it known that I, RALPH W. SOHL, a citizen of the United States, and resident of Akron, Ohio, have invented new and useful Improvements in Vulcanizing Apparatus, of which the following is a specification.

My invention relates to pneumatic cores adapted to be used for vulcanizing purposes in connection with the repair of pneumatic tire casings, and it relates more particularly to means for heating the same.

The object of my invention consists in providing a novel fluid introducing apparatus of the character designated, whereby the pneumatic core may be maintained at any desired temperature and pressure.

Heretofore, in the manufacture of pneumatic cores of the type in question, commonly called air bags, it has been customary to inflate the same by means of a single air connection disposed at one end thereof. This air connection serves to maintain the pressure within the bag, but it does not contribute to the heating thereof. All of the heat for the cure must be transmitted from the externally disposed mould against which the air bag holds the casing. The main objection to this type of air bag is that the portion of the rubber of the casing adjacent the heated mould must receive more heat than is necessary to properly cure the same, in order to transmit a sufficient quantity of heat to cure that portion of rubber which is disposed adjacent to the air bag, thus frequently over-curing the portion adjacent to the heated mould.

In order to overcome this objection, bags of different type have been provided with a steam intake connection at one end and an exhaust connection at the opposite end, which is provided with a valve. The exhaust connection is necessary, since the condensation of the steam would, in a few minutes, fill the bag with water of condensation, if a drain were not present. These bags have been provided with the steam connection disposed at one end and the drain at the opposite end. This is objectionable because it necessitates puncturing the bag at two points with the accompanying disadvantage of providing two fluid-tight connections thereto.

By my invention, I have eliminated the objection to the air bag of providing no

heat to the inner surface of the casing being cured, and have also eliminated the objection of the double connection to the steam-heated bag, by combining the steam intake and exhaust ports into a single unitary device which may be inserted at one end of the bag. This necessitates but a single fluid-tight connection, and at the same time permits of the introduction and escape of live steam for heating and inflating the bag at one end thereof.

For better understanding of my invention, reference may now be had to the accompanying drawing, which is a side elevational view of an air bag provided with a unitary steam inlet and exhaust port constructed in accordance with my invention.

In the structure illustrated in the drawing is an inflatable bag 1 composed of reinforced rubber or the like, at one end of which is inserted a member 2 comprising a pipe 3 of relatively large diameter, which extends through the wall of bag 1 into communication with the interior thereof, and is connected by means of a hose connection 4 to a source of supply of live steam of any desired pressure. The pipe 3 must be connected to the bag 1 in such manner as to be fluid tight. Disposed within the pipe 3 is a relatively long hollow pipe 5 of relatively small diameter, which extends into the central portion of the bag 1 and extends through the pipe 3, but not in communication therewith, being connected to a tube 6 provided at its opposite end with a valve member 7.

Having described the structure of my invention, the operation thereof is as follows. The bag 1 is disposed within a pneumatic tire casing to be vulcanized, and an external pressure applying device is mounted on the outside thereof so as to prevent the expansion of the casing with the expansion of the tube 1. The external pressure applying device usually consists of a metallic core which is adapted to be heated, but may, if desired, consist of layers of cloth wrapped thereabout. Steam is admitted through the tube 4 and the pipe 3 to the air bag 1 and after heating of the bag is permitted to escape through the pipe 5 and the tube 6. The valve 7 may be left entirely open if it is desired merely to heat the bag 1 by means of the steam contained therein, but if it is desired to also employ the bag as a pressure producing device, valve 7 should be substan-

tially closed, so as to permit the escape of only the condensed steam, or only of a sufficiently small amount of steam not to interfere with maintaining the desired pressure

5 within the bag 1.

The pipe 5 is of sufficient length to reach into the center of the air bag in order that it may extend into any pool of condensed steam which may accumulate therein. The 10 pipe may, of course, be bent into any desired shape prior to being inserted into the bag 1.

Although I have illustrated but a single form of my invention and have described in 15 detail but a single application thereof, it will be apparent to those skilled in the art that it is not so limited but that various minor modifications and changes may be made therein without departing from the 20 spirit of my invention or from the scope of the appended claims.

What I claim is:

1. A pneumatic core for vulcanizing purposes comprising an inflatable bag member, 25 and unitary means provided with a plurality of passageways associated therewith for admitting a fluid thereto and permitting the escape of said fluid therefrom.

2. A pneumatic core for vulcanizing purposes comprising an inflatable bag member, 30 and means disposed at one end of said bag

member in communication with the interior thereof and adapted to simultaneously admit a fluid into said bag and permit the escape thereof.

35

3. A pneumatic core for vulcanizing purposes comprising an inflatable bag member, and a unitary means inserted in said member adapted to permit the introduction of a fluid at one point in said bag and permit the 40 escape of said fluid from point removed from the point of entrance.

40

4. A pneumatic core for vulcanizing purposes comprising an inflatable bag member, and unitary means inserted at one end of 45 said member comprising a fluid inlet port and a tube member extending into said bag member and adapted to permit the escape of the fluid.

45

5. A pneumatic core for vulcanizing purposes comprising an inflatable bag member and unitary means inserted at one end of said member comprising a fluid inlet tube and a relatively smaller tube disposed within 50 said inlet tube but not in communication therewith extending into the central portion of said bag and adapted to permit the escape of the fluid therefrom.

55

In witness whereof, I have hereunto signed my name.

RALPH W. SOHL.
